UNITED STATES PATENT OFFICE.

ALBERT J. COBURN, OF NEW ORLEANS, LOUISIANA.

FLUSHING APPARATUS.

1,165,228.

Specification of Letters Patent. Patented Dec. 21, 1915.

Application filed June 24, 1915. Serial No. 36,110.

To all whom it may concern:

Be it known that I, ALBERT J. COBURN, a citizen of the United States, residing at New Orleans, in the parish of Orleans and State 5 of Louisiana, have invented new and useful Improvements in Flushing Apparatus, of which the following is a specification.

My present invention pertains to flushing apparatus of the kind in which a casing is 10 moved vertically to start a siphon action; and it contemplates the provision of an apparatus that is in general simple and compact in construction, reliable in operation, and well adapted to withstand the rough 15 usage to which hand-actuated apparatus is ordinarily subjected.

The invention also contemplates the provision in the down pipe of a siphonic flushing apparatus, of a construction calculated 20 to hold back a portion of the water and in that way contribute to the reliable action and general efficiency of the apparatus notwithstanding the simplicity thereof and the small number of parts it comprises.

Other advantageous features of the invention will be fully understood from the following description and claims when the same are read in connection with the drawings, accompanying and forming part of 25 this specification, in which:

Figure 1 is a vertical section showing the best practical embodiment of my invention that I have as yet devised. Fig. 2 is an enlarged horizontal section taken in a plane 30 above the non-return means of the casing, as indicated by the line 2—2 of Fig. 1. Fig. 3 is an enlarged detail elevation showing the side valve that I prefer to employ for the passage of water from the tank to the 35 interior of the vertically-movable casing subsequently to the first flow of water down the down pipe.

Referring by numeral to the said drawings: 1 is a flushing tank designed to be 40 supplied with water in the conventional manner or any other manner compatible with the purpose of my invention, and 2 is the down pipe clamped or otherwise suitably fixed to the bottom wall of the tank 1 45 and extending upwardly therein as shown. The said down pipe 2 is provided in its lower portion with a contraction 3 for an important purpose hereinafter set forth, and at its lower end the down pipe is 50 designed to be connected with the usual pipe

(not shown) to lead flushing water to a water closet bowl.

4 is the vertically-movable casing which surrounds the down pipe 2 in the tank 1, and is designed to be connected at its upper 50 end to a lever 4^a or other means through the medium of which it may be conveniently raised. The said casing is preferably, though not necessarily, of even diameter throughout its height, and in its lower end 55 wall 5, which snugly surrounds the down pipe 2, are apertures 6, designed to enable the water in the tank 1 to seek its level in the casing.

Any suitable non-return means may be 60 employed to normally permit the upward passage of water through the apertures 6 and check the return thereof when the casing 4 is raised with water therein. I prefer, however, to employ for the purpose the 65 semi-annular clack valves 7, preferably of sheet-metal, which are hinged at 8 to the casing 4 and are designed to normally rest on the bottom wall of the casing or slightly above said bottom wall.

Formed in the side wall of the casing 4 is an opening 9 which is preferably, though not necessarily, provided to permit water to 70 pass from the tank 1 into the casing 4 after the siphon action. The said opening 9 is 75 controlled by an inwardly opening clack valve 10, hinged to the casing wall as indicated by 11.

The contraction 3 in the down pipe is arranged in a plane adjacent to the bottom of 80 the tank; the said contraction in the present embodiment being formed in a casting which forms the lower part or a continuation of the down pipe. In practice the contraction 3 serves to bring the water into 85 small compass—*i. e.*, contracts the descending body of water, and cuts out all air, and this without materially lessening the volume of water which contributes to the production of a perfect vacuum in the casing.

While I prefer for the reason stated to employ the valve 10 as well as the non-return means at the bottom of the casing 4, I would have it distinctly understood that when desired the non-return means at the 105 bottom of the casing may alone be employed or the non-return means or valve 10 at the side of the casing may alone be employed without departure from the scope of my claimed invention.

110

In practice water supplied to the tank 1 enters and seeks its level in the casing 4, while said casing is in the position shown in Fig. 1, relative to the pipe 2. Then, when 5 the casing 4 is raised, the weight of the water therein will close the non-return means of the casing, and the water in the casing will be carried above the upper end of the pipe 2 whereupon it will operate to 10 start the siphon action. After the water starts to flow down the pipe 2, outward pressure on the valves is relieved and hence the water in the tank is able to unseat said valves and enter the casing; the valve 9 at 15 this time serving to permit a large volume of water to pass from the tank to the casing which makes the employment of said valve 9 preferable. Subsequently to the operation described, the casing 4 gravitates to the position shown in Fig. 1 so as to be ready for another operation. The flared mouth 2^a tends to throw water to the vertical center of pipe 2 which has the effect of sealing the pipe against the entry of air through the 25 closet duct.

Having described my invention, what I claim and desire to secure by Letters-Patent, is:

1. In a flushing apparatus, the combination of a tank, a down pipe therein, a vertically-movable casing also arranged in the

tank and surrounding the down pipe and having an apertured bottom wall and an apertured side wall, non-return means in the casing complementary to the aperture in the bottom wall and the aperture in the side wall, respectively, and means through the medium of which the casing may be raised.

2. In a flushing apparatus, the combination with the bottom wall of a flushing tank, a casting arranged in said bottom wall and having an interior contraction and an exterior thread and also having a flange to bear against one side of the tank wall, a threaded clamping ring mounted on the casting and arranged to bear against the other side of said tank wall, a down pipe threaded on the upper portion of said casting, a casing surrounding said down pipe and having an aperture for the entry of water from the tank and non-return means for controlling said aperture, and means through the medium of which the casing may be raised.

In testimony whereof I have hereunto set my hand in presence of two subscribing witnesses.

ALBERT J. COBURN.
